Primary Examiner — T. Chase Nelson(74) Attorney, Agent, or Firm — Geiser Law, PLLC; Greg N. Geiser(57) CLAIM

The ornamental design for a patterned shoe sole, as shown and described.

DESCRIPTION

FIG. 1 is a side view of the patterned shoe sole as seen on a shoe;

FIG. 2 is a top plan view thereof; and,

FIG. 3 is a bottom plan view thereof.

The broken lines shown in the figures are for environmental purposes only and form no part of the claimed design.
